W. W. DAKE.
ELASTIC FLUID TURBINE.
APPLICATION FILED JAN. 23, 1911.

1,035,544.

Patented Aug. 13, 1912.

UNITED STATES PATENT OFFICE

WILFORD W. DAKE, OF MUSKEGON, MICHIGAN, ASSIGNOR TO PYLE-NATIONAL ELECTRIC HEADLIGHT COMPANY, OF CHICAGO, ILLINOIS, A CORPORATION OF NEW JERSEY.

ELASTIC-FLUID TURBINE.

1,035,544.

Specification of Letters Patent. Patented Aug. 13, 1912.

Application filed January 23, 1911. Serial No. 604,085.

To all whom it may concern:

Be it known that I, WILFORD W. DAKE, a citizen of the United States, residing at Muskegon, in the county of Muskegon and State of Michigan, have invented new and useful Improvements in Elastic-Fluid Turbine-Engines, of which the following is a specification.

My present invention relates to elastic fluid turbine engines, and its object is to provide improved passage-containing members or "passage blocks" through which the fluid is delivered or redelivered to the rotor buckets. This object is attained by, and my present invention is embodied in, the mechanism hereinafter described, illustrated by the accompanying drawings, in which:

Figure 1 is a section of my passage-block and of a part of the rotor, taken on line S—S of Fig. 2, being on a plane at right angles to the rotor's axis: Fig. 2 is a section of said passage-block taken on a line corresponding with the arc line X—X of Fig. 1: and Fig. 3 shows the same parts seen in Fig. 2, in the same relative position, and viewed from the same direction, but separated from each other, and no part being sectioned.

My passage block is detachably fastened as by screws 1 to the supporting frame, as the rotor casing 40 (shown broken away in Fig. 2) of the turbine engine. The body portion 2 of the passage block has preferably a low lug 3 adapted to be surfaced to provide a close contact with such casing. A second lug 4 on the opposite side of the body 2 is likewise adapted to be surfaced to provide a close joint with the nozzle passage block 5, a thin metal tightening and wearing piece or washer 6 being interposed. The elastic fluid, hereinafter called steam, is admitted from suitable supply pipes (not shown), by the opening 7 through the body 2, its lugs 3 and 4 and the washer 6, into the passage 8 formed in the inner face of the nozzle passage block 5, such passage continuing to form the nozzle 9, whence the steam is delivered to the buckets of the rotor 10, a segment of which only is shown in Fig. 1.

It will be seen that the washer 6 may, when worn, be easily removed and replaced. The steam being delivered from the nozzle 9 to rotor buckets 11 and 12 and exerting

this, its first driving impulse on the rotor, 55 emerges from such buckets into passages 13 and 14 of the outer or primary passage block, when it is, by the walls of such passages, redelivered to buckets at that time opposite the discharge vents of such passages, as the buckets 15, 16, 17, 18 and 19. After exerting this, its second driving impulse on the rotor, the steam passes from such buckets into the passages 20 and 21 of the inner or secondary passage block, 65 when it is, by the walls of such passages, again redelivered to buckets at that time opposite the vents of such passages, as the buckets 22, 23, 24, 25, 26 and 27, and, after exerting this, its third driving impulse on 70 the rotor, escapes.

The various passages in the outer and inner passage blocks are formed with their two opposite side walls converging toward their discharge vents, as seen in Fig. 2 illustrating the construction of the inner passage block, the construction of the outer passage block as to such converging side walls being similar.

The outer and inner passage blocks are 80 formed in separate members or halves, half or a part of the passages being formed in the inner face of each member, so that such half passages register when such members are assembled, as seen in Figs. 2 and 3, the 85 construction of the outer passage block being similar to that of the inner block in this respect also. The two members of the inner block are indicated by the numerals 30 and 31, respectively, one of the members 90 of the outer block being indicated by the numeral 32. The half blocks may be readily separated for cleaning the passages, and are held together and supported by screws 28 for the inner block, and 29 for the outer 95 block. It will be seen that by forming the passages in the face of these various blocks, economy and easy manufacture are attained.

My invention may be embodied in varying mechanisms, and I do not propose to confine myself to the construction shown and described.

I claim:

1. In a machine of the character described, a frame, a rotor, primary and secondary passage blocks, a nozzle passage block, all said blocks having passages de-

livering the driving fluid to the rotor, and a supporting member carrying said blocks and removably secured to the frame.

2. In a machine of the character described, a passage block comprising detachably connected members, one of which has formed in its plane face adjacent the other member a passage through which the driving fluid is delivered to the rotor.

10 3. In a machine of the character described, a passage block comprising detachably connected members and a wearing plate held between them, one of said members having formed in its face adjacent the other member a passage through which the driving fluid is delivered to the rotor.

4. In a machine of the character described, a frame, a rotor, a nozzle block, a passage block through which the driving fluid is received from and redelivered to the rotor, a supporting member for the blocks and having a supply passage communicating with the nozzle block's passage, both said blocks being detachably connected to said member, and said member being detachably connected to the frame.

5. In a machine of the character described, a passage block comprising detachably connected members, each having formed in its face adjacent the other member a passage through which the driving fluid is delivered to the rotor, said passage in each registering with the passage in the other member.

30 6. In a machine of the character described, a passage block comprising detach-

ably connected members, each having formed in its face adjacent the other member a passage through which the driving fluid is delivered to the rotor, said passage in each 40 registering with the passage in the other member, and the depth of each passage below the said surface of its block diminishing toward the discharge vent of such passage.

45 7. In a machine of the character described, a passage block comprising detachably connected members, one of which has formed in its face adjacent the other member a passage through which the driving fluid 50 is delivered to the rotor, the depth of such passage below the said surface of its block diminishing toward the discharge vent of the passage.

8. In a machine of the character described, a frame, a passage block comprising detachably connected members, each having formed in its face adjacent the other member a passage through which the driving fluid is delivered to the rotor, said passage 55 in each registering with the passage in the other member, and a supporting member for the passage block, the supporting member and other said members being detachably connected together and to the frame.

60 In testimony whereof I have hereunto set my hand in presence of two subscribing witnesses.

WILFORD W. DAKE.
